UNITED STATES PATENT OFFICE.

CURTIS C. LILLIBRIDGE, OF HUTCHINSON, KANSAS.

ELECTRIC HEATING-COIL.

1,100,585.

Specification of Letters Patent. Patented June 16, 1914.

Application filed July 21, 1913. Serial No. 780,328.

To all whom it may concern:

Be it known that I, CURTIS C. LILLIBRIDGE, a citizen of the United States, residing at Hutchinson, in the county of Reno and State 5 of Kansas, have invented certain new and useful Improvements in Electric Heating-Coils; and I do declare the following to be a full, clear, and exact description of the invention, such as will enable others skilled in 10 the art to which it appertains to make and use the same.

This invention relates to improvements in electric heating coils.

One object of the invention is to provide 15 an electric heating coil having an improved construction and arrangement of insulating or non-conducting plates which are bound to a combustible separating and spacing material by the current conducting coil, said 20 combustible separating material being carbonized or burnt up by the heat generated from the coil, thus forming a space between the non-conducting sheets or plates in which the ashes from the burnt paper are disposed, 25 said space preventing the coil from becoming overheated while the paper ashes remaining between the two sheets or plates act as a heat resistance as well as an insulator, thus saving the use of mica or other form of insu- 30 lator and producing much better results than a solid core of mica or other insulation.

Another object is to provide an electric heating coil which may be arranged in different ways for use in various kinds and 35 shapes of electric heating elements or electrically heated devices.

With these and other objects in view, the invention consists of certain novel features of construction, and the combination and 40 arrangement of parts as will be more fully described and claimed.

In the accompanying drawings: Figure 1 is a perspective view of one of my improved electric heating coils; Fig. 2 is a longitudinal section thereof; Fig. 3 is a cross section of the same; Fig. 4 is a side view of a portion of a slightly modified form of the coil; Fig. 5 is a plan view of one form of an electric heating element showing the top plate 45 thereof broken away and illustrating one application and arrangement of my improved heating coil; Fig. 6 is a cross sectional view thereof taken on the line 6--6 of Fig. 5.

55 In the embodiment of the invention I provide plates or sheets 1 which are preferably

constructed of mica but which may be porcelain or any other suitable non-conducting, fire-proof or heat resisting material. The plates or sheets 1 may also be of any desired size and shape, the same being here shown as constructed in the form of long narrow strips and as preferably having in their opposite edges series of notches 2 as shown in Fig. 1 of the drawing, but which if desired may be constructed without the notches as shown in Fig. 4 of the drawing. The purpose of the notches 2 will be hereinafter described. The plates or sheets 1 are separated or spaced apart by strips or pieces 3 of combustible material which are preferably in the form of blotting paper, but which may be of any suitable material capable of being consumed or carbonized under the action of the heat produced by the coil. The 70 plates or sheets 1 and the strips 3 are bound by the current conducting wire or tape 4 and thus form the core of the coil wound thereon. The current conducting tape or wire 4 is wound spirally around the sheets 1 and when the latter are notched the coils of the wire are engaged with the notches and are thus held in evenly spaced relation, as shown in Fig. 1 of the drawings. In thus 75 constructing the coil the paper or combustible strip between the plates or sheets 1 will be consumed or carbonized by the heat produced from the electric current when sent through the wire or tape 4 of the coil and when the strips 3 are thus burned a space is 80 left between the non-conducting and non-combustible plates 1 which will prevent the coil from becoming overheated while the thin 85 layer of burnt or carbonized paper remaining between the plates or sheets 1 serves as a heat resisting element which not only saves the use of additional sheets of insulating material but has been found to be a great improvement over a solid core of mica or other insulating material.

100 My improved coils when constructed as herein shown and described may be employed in connection with any electrically heated appliances and may be arranged in various ways to accommodate the same to the use of different shapes and sizes of electrical heating elements. In Figs. 5 and 6 the coils are shown as arranged for use in connection with a circular heating element or hot plate α and when thus used three 105 coils are preferably employed and are arranged in substantially triangular form be-

tween upper and lower plates 5 of copper or other suitable material which form a casing for the coils. The edges of the plates 5 are turned inwardly to provide right angular flanges 6 which form the side edges of the casing. The plates 5 are fastened together in any suitable manner to form the casing, the same being shown in the present instance as being connected by rivets 7 arranged therethrough adjacent to the inner sides of the adjoining ends of the coils. The triangular or other shaped space between the coils when arranged in the manner described is preferably filled by a core 8 of suitable insulating material.

The free ends of the wires from the coil are connected at a suitable point in the casing to terminal strips 9 of copper or other suitable material which are separated by sheets 10 of mica or other suitable material from the upper and lower plates of the casing, the outer ends of said terminal strips having suitable binding posts or other connections for the ends of the current conducting wires to which the heating element is connected.

By arranging the coils in a casing as shown in Figs. 5 and 6 of the drawings they may be conveniently handled and readily applied to the hot plates or other parts of electric cookers or ranges and to any other forms of electrically heated appliances.

From the foregoing description taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of the invention as claimed.

Having thus described my invention, what I claim is:

1. An electric heating coil comprising sheets of non-conducting and non-combustible material, a current conducting wire coiled around said sheets, and ash made from strips of combustible material clamped between said sheets.

2. An electric heating coil comprising strips of mica having registering notches in their edges, a current conducting element coiled around said strips and lying within said notches, and an ash clamped between said strips and constituting a core holding such strips separated.

3. An electric heating element comprising a casing consisting of upper and lower plates, heating coils arranged between said plates, said coils comprising spaced non-combustible sheets of insulating material, current conducting wires coiled around said sheets, carbonized strips disposed between said sheets, and an insulating core arranged between said plates of the casing and within the inclosure formed by said coils.

In testimony whereof I have hereunto set my hand in presence of two subscribing witnesses.

CURTIS C. LILLIBRIDGE.
